UNITED STATES PATENT OFFICE

CLARENCE LIPPER, OF PHILADELPHIA, PENNSYLVANIA

DESIGN FOR BRAID

Application filed August 30, 1928. Serial No. 27,991. Term of patent 3½ years.

To all whom it may concern:

Be it known that I, CLARENCE LIPPER, a citizen of the United States, residing at Philadelphia, in the county of Philadelphia and State of Pennsylvania, have invented a certain new, original, and ornamental Design for Braid, of which the following is a specification, reference being had to the accompanying drawing, forming part thereof.

I claim:

The ornamental design for braid, as shown.

CLARENCE LIPPER.
